ABSTRACT OF THE DISCLOSURE

A shielding system for protection against radiation for the horizontal tubular support of a remote-control master-slave manipulator. The system comprises a plurality of at least two spaced apart barrier walls of radiation absorptive material tightly fitted within the tubular support. These barrier walls are penetrated by slots for passage of the tie rods, tapes and/or cables by which motion is transmitted from the master arm to the slave arm. The slots in one barrier wall are offset with respect to the corresponding slots in another barrier wall so as to be out of alignment so that no straight line radiation path exists through the horizontal support.

This invention relates to shielding for the interior of the horizontal support or through tube of through-the-wall remote-control master-slave manipulators. Such master-slave manipulators comprise generally a master arm and a slave arm, each pivotally connected to one of the opposite ends of a generally horizontal tubular support which extends through a generally vertical shielding wall. The through tube is mounted in a sleeve or tube set in the wall so as to permit rotation of the through tube about its longitudinal axis with resulting transmission of side-to-side or X motion from the master arm to the slave arm. Typical of such manipulators are those shown in Jelatis et al. United States Patents No. 2,888,154 issued May 29, 1959 and No. 3,139,990 issued July 7, 1964.

The most common use of such manipulators is in the handling of radioactive materials in a dangerous area on one side of a barrier wall from a safe area on the opposite side of that wall where the operator is positioned. The hazardous rays and particles emitted from such dangerous substances as may be handled with the manipulator tend to travel along straight line paths of varying length. In order to prevent endangering of personnel due to the escape of harmful radioactive products, such as gamma radiation, through the opening in the barrier wall through which the manipulator extends, pains must be taken to minimize or eliminate any straight line path by which harmful radiation can escape to the safe side of the barrier wall.

The present invention is directed to a shielding system for the interior of the through tube and, in most instances, this interior shielding will be used in conjunction with a shielding system for the annular space between the manipulator through tube and the opening through the barrier wall in which that through tube fits, as described and claimed in copending application Ser. No. 529,058, filed Feb. 21, 1966. The invention of that application in turn relates to shielding in the annular space between the through tube and wall opening when the through tube is supported on truck mounts as described and claimed in copending application Ser. No. 529,057, filed Feb. 21, 1966, now Patent No. 3,410,418.

The invention is illustrated by the accompanying drawing in which the same numerals refer to corresponding parts and in which:

2

FIGURE 1 is an elevation, partly in section, along a vertical plane extending along the longitudinal axis showing a through tube of a master-slave manipulator mounted in a barrier wall and utilizing roller truck mounts and annular shielding and utilizing interior labyrinth shielding according to the present invention;

FIGURE 2 is a section on the line 2—2 of FIGURE 1 and in the direction of the arrows;

FIGURE 3 is a section on the line 3—3 of FIGURE 1 and in the direction of the arrows;

FIGURE 4 is a section on the line 4—4 of FIGURE 1 and in the direction of the arrows; and

FIGURE 5 is a fragmentary perspective view showing connection of tie rods.

Referring now to the drawing and particularly to FIGURE 1, there is shown the horizontal support or through tube 10 of a remote control master-slave manipulator. The through tube 10 extends through a protective shielding or barrier wall 11 which is of substantial thickness. The opening for passage of the through tube through wall 11 is ordinarily fitted with a tube or sleeve 12. In the configuration illustrated, through tube 10 is supported within sleeve 12 by a master roller truck mount assembly 13 at one end and a slave roller truck mount assembly 14 at the other end. The structure of the roller truck mounts is described and claimed in detail in the copending application referred to above. The roller truck mounts per se form no part of the present invention. The through tube 10 is supported for rotation about its longitudinal axis by means of a plurality of generally transversely extending rollers 15 journaled for rotation and mounted in the opposite edge faces of the rings which form the bodies of the roller truck mounts.

An annular space 16 exists between the inner wall surface of sleeve 12 and the outer wall surface of through tube 10. Within this space are installed annular shielding in assemblies of two general types as described and claimed in the aforesaid copending application. Annular shielding assembly 17 is an inside diameter assembly fitted with a tight fit against the outer periphery of through tube 10 but with clearance with respect to the inner periphery of sleeve 12. The other of these annular shielding assemblies 18 is an outside diameter assembly fitted with a tight sealing fit against the inner periphery of sleeve 12 but with clearance relative to through tube 10. Shielding assembly 18 is stationary and the through tube rotates within it. The shielding assembly 17 rotates with the through tube. It will be seen that these shielding assemblies define a labyrinthine passage through the annular space through which substances cannot pass in a straight line.

The labyrinth shielding according to the present invention fits within through tube 10. It is composed of at least two circular assemblies of two different general types indicated at 19 and 20, respectively. The assemblies are spaced apart longitudinally and extend transverse to the longitudinal axis of tube 10. Each of the assemblies is desirably a laminated structure composed of a plurality of segments in face-to-face abutment. The segments are composed of radioactive absorptive material and are assembled to make up the required thickness to give the desired protection. Typically each segment is about one inch thick and each shielding assembly is composed of from one to six segments. The most common of these absorptive materials for gamma ray shielding are lead and lead based alloys, such as lead-antimony, lead-tin, etc. Materials of large hydrogen content like synthetic resins, such as polyethylene, and waxes such as paraffin and the like, may also be used for more effective shielding of neutron emissions. The edges of the assemblies fit in close engagement with the inside wall of tube 10.

As is well understood in the manipulator art, the back and forth or Y motion of the master arm toward and

away from the barrier wall 11 is transmitted to the slave arm by means of tie rod assemblies 21. As here illustrated, each tie rod assembly 21 comprises a single rod 22 at the slave end joined through a fitting 23 to a parallel pair of rods 24 extending to the master end. This avoids the necessity for providing a longitudinal straight line passage for the tie rods. Instead, passage for the tie rods through the shielding assemblies is provided by means of vertical slots 25 in assembly 20 for passage of single tie rods 22 and spaced parallel vertical off-set slots 26 in assembly 19 for double tie rods 24. It will be noted that slots 25 are in the top and bottom edges of the shielding assembly 20 and are aligned generally with the vertical center line plane when the through tube is in its normal at-rest position. Slots 26 are also in the top and bottom edges of assembly 19 and are spaced on either side of that same vertical center line plane by a total distance which is greater than the width of slot 25. In this manner it is insured that the slots are off-set from one another sufficiently to eliminate any direct straight line passage through the through tube along the paths of the tie rod assemblies. At the same time there is no interference by the shielding members with movement of the tie rod assemblies and transmission of Y motion.

Other motions are transmitted from the master arm of the manipulator to the slave arm by means of linear motion transmission members 27, such as tapes and cables, passing through the horizontal through tube 10, as is well known in the art. These motions include movement of the arms along their own longitudinal axes of Z motion, actuation of the tong members on the end of the slave arm in response to actuation of the handle on the end of the master arm and rotation of the tong means about each of three axes in response to corresponding rotation of the handle. To provide for movement of flexible linear motion transmission members 27, either tapes or cables, through the shielding assemblies 19 and 20, there are provided relatively narrow longitudinal slots 28 and 29, respectively.

Slots 28 and 29 are disposed generally along the horizontal center line plane of the shielding assemblies when the through tube is at its normal at-rest position. Each slot 28 and 29 has a depth extending all of the way through the shielding assembly, a length sufficient to carry the required number of linear motion transmission members 27 and a width sufficient to permit the free 45 passage of those members through the shielding assemblies without binding. Typically the length may be about 4 inches and the width about $\frac{1}{8}$ to $\frac{3}{8}$ inch.

To facilitate free movement of the tapes and cables slots 28 and 29 are desirably aligned with one another 50 and with the edges of the pulleys on the master and slave arms by which they are guided into the through tube. The slots 28 and 29 have relatively small cross-sectional area compared with the cross-sectional area of tube 10, and they are spaced apart longitudinally by a relatively great 55 distance. Any hazardous ray or emitted particle whose path of travel is precisely aligned with the slots will pass through the tube 10. However, even though the slots 28 and 29 may be in precise alignment, the operator at the master slave end of the through tube is relatively safe from exposure to dangerous radioactive products, because the predominant portion of the cross-sectional area of the through tube is thoroughly shielded to prevent straight line transmission of harmful radioactive products.

Where the utmost in safety is desired, one of the inside shielding assemblies, indicated generally at 19A, is provided with a slot 28A for passage of the tapes and cables which is offset vertically with respect to slots 28 and 29 by a distance greater than the width of the slot openings. Assembly 19A is similar in all respects to assembly 19 except for the location of slot 28A. In order to permit free passage of the tapes and cables through the off-set slot 28A without binding, means are provided for altering the path of travel of the members 27, guiding them through the off-set slot and returning them to their normal path.

These guide means 30 are secured to the inside wall of the tube 10 and include a frame or bracket 31 which is bifurcated to support a pair of parallel shafts 32 on which are journaled a plurality of pulleys 33, each adapted to carry a tape or pulley. The banks of pulleys 33 are disposed so that the guiding tracks of one bank are tangent to a plane extending through the normal slots 28 and 29 and the opposite guiding tracks of the adjacent pulley bank are tangent to a parallel plane extending through off-set slot 28A. One set of guide means is disposed on each side of the shielding assembly with the off-set slot. It will be readily seen in FIGURE 1 that the linear motion transmission members 27 are diverted from their normal path through the off-set slot 28A and back to the normal path while insuring free passage of these members through the through tube. Any chance radioactive particle which finds its way through slot 29 in shielding assembly 20 will as it travels along its straight line path be absorbed by the shielding assembly 19A.

The positions of the segments comprising the shielding assemblies can be maintained with respect to one another by any conventional means. For example, the inside surface of through tube 10 may be provided with keys and the shielding segments with corresponding keyways, or the segments may be screwed to the through tube or the like.

What is claimed is:

1. A labyrinthine radiation shielding system for the interior of the horizontal tubular support of a remote-control master-slave manipulator in which Y motion is transmitted through tie rod assemblies, said shielding system comprising:
  - (A) at least two longitudinally spaced apart shielding assemblies disposed in the horizontal tubular support of a manipulator,
  - (B) said shielding assemblies
    - (1) extending transverse to the longitudinal axis of said tubular support,
    - (2) being composed essentially of a radiation absorptive material, and
    - (3) fitted in close engagement with the interior wall of said tubular support,
  - (C) one of said assemblies being provided with a central vertically extending radial slot for passage of a tie rod,
  - (D) another of said assemblies being provided with a pair of parallel vertically extending slots for passage of a pair of tie rods, said slots being spaced apart laterally on opposite sides of a plane extending through said first slot passage by a distance greater than the width of said first passage, and
  - (E) each of said assemblies being provided with a relatively narrow horizontal slot for passage of linear motion transmission elements therethrough.
2. A shielding system according to claim 1 further characterized in that said shielding assemblies are each provided with vertically aligned and vertically spaced apart slots for passage of rods extending inwardly from the top and bottom edges, respectively, of said assemblies.
3. A shielding system according to claim 1 further characterized in that said assemblies are composed of a plurality of flat slab-like segments disposed in abutting face-to-face relation and composed essentially of a radiation absorptive material.
4. A shielding system according to claim 1 further characterized in that each of said assemblies ranges from about one to six inches in thickness.
5. A shielding system according to claim 1 further characterized in that at least one of said horizontal slots is disposed generally along the horizontal center line plane.
6. A shielding system according to claim 5 further characterized in that at least another one of said horizontal slots is disposed in a plane parallel to but off-set vertically from the horizontal center line plane whereby said slots are out of alignment and guide means are provided

to direct linear motion transmission elements in their paths through said slots.

7. A shielding system according to claim 6 further characterized in that said guide means comprises a pair of banks of pulleys disposed on each side of said shielding assembly with off-set horizontal slot, said banks of pulleys being journaled on pairs of parallel horizontal shafts supported from the walls of the horizontal tubular supports, said off-set horizontal slots being spaced apart vertically a distance greater than the vertical opening of said slots, said pulley banks being disposed between the horizontal planes extending through said horizontal slots with their guiding faces generally tangential to said planes.
